UNITED STATES PATENT OFFICE.

HAROLD W. FLETCHER, OF HOUSTON, TEXAS, ASSIGNOR TO HUGHES TOOL COMPANY,
OF HOUSTON, TEXAS, A CORPORATION OF TEXAS.

ROTARY DRILL CUTTER.

Application filed September 13, 1920. Serial No. 410,038.

To all whom it may concern:

Be it known that I, HAROLD W. FLETCHER, a citizen of the United States, residing at Houston, Harris County, Texas, have invented a certain new and useful Improvement 5 in Rotary Drill Cutters, of which the following is a full, clear, and exact description, such as will enable others skilled in the art to which it appertains to make and use 10 the same.

My invention relates to an improvement in rotary cutters adapted for use on roller earth-boring drills.

In rotary drills adapted for boring wells 15 in earth and rock for water, oil, gas, sulfur, etc., a cutter such as is disclosed in connection with this application is frequently used. This type of cutter is mounted upon a bearing, which is secured to a pin forming 20 a part of the head of the drill. The cutter is adapted to rotate upon the bearing, which is preferably formed within a recess in the inner face of the cutter, in such manner that the bearing may not be removed 25 from the rotating cutter. With the bearing thus formed within the cutter, it is necessary to provide a means for holding the cutter and bearing non-rotatably together so that the bearing may be threaded upon 30 the pin to which it is secured. To do this it has been customary to form a radial opening in the cutter which is adapted to index, when in proper position, with a recess in the bearing. Thus by placing a pin through the 35 opening in the cutter and fitting the pin also within the recess in the bearing, the cutter and bearing together may be rotated to thread the bearing upon the pin. The opening, through which the wrench or pin is 40 inserted to secure the cutter and bearing together, must, during the operation of the drill, be plugged up by means of a set screw or other similar device. A great deal of difficulty is ordinarily experienced in getting 45 a set screw which will fit firmly within this opening and which will not be easily removable during the operation of the drill.

An object of my invention is to provide 50 a means for filling the opening in the cutter, which may be readily applied and which will not be accidentally lost during the operation of the drill.

Another object is to provide a means for 55 filling the opening in the cutter, which will

fit openings of various sizes and which may 55 be removed without difficulty, and by means of tools ordinarily to be found about a drilling rig.

Other objects and advantages will appear more clearly in the specification which follows, and the specific details of novelty will be pointed out with particularity in the claims.

Referring to the drawing forming a part 60 of this specification, and wherein like numerals of reference are applied to like parts throughout the several views, Fig. 1 is a central longitudinal section through the stub shaft or pin, upon which the cutter is mounted, and showing the bearing and cutter attached thereto; Fig. 2 is a transverse section on the line 2-2 of Fig. 1, showing the manner of inserting the wrench; Fig. 3 is a longitudinal section of a plug of compressible material, which is used with my invention; Fig. 4 is a side elevation of the wrench used 70 in applying my invention; and Fig. 5 is a broken detail showing a means of indexing the openings in the cutter and bearing so that the plug may be removed. 75

The cutter shown in the drawings is a type 80 of cutter ordinarily used in connection with the bit shown in the patent to Hughes, No. 1,010,406. The improvement is designed for use particularly in connection with the cutter bearing described in my co-pending application No. 410,038, filed September 13, 1920, now Patent No. 1,399,856 issued December 13, 1921. This cutter is especially 85 adapted for use in hard material, such as rock, and comprises a roller having a frustoconical forward cutting face, with longitudinal teeth 6 thereon and radial cutting teeth 7 on the truncated forward end to act upon the material. The inner end of the cutter 90 is beveled inwardly at 8 from the point 9 of largest diameter and toothed at 10 to act upon the side of the hole. The inner end of the cutter has a flat face 11 adapted to bear against the head of the bit. The bearing 12, upon which this cutter rotates, is shaped substantially in the same manner as the cutter itself. The cutter has an inner bearing recess to receive the bearing and it is contemplated that this bearing shall 100 be formed integrally within the recess so that it may not be removed from the cutter. The bearing 12 has a large threaded recess 13

therein to receive the stub shaft 14 secured to the forward end of the head of the drill upon which it is mounted. The outer end of the stub shaft 14 is reduced in diameter 5 at 15 to form a further support for the bearing, this reduced portion being smooth, as shown in the drawing.

A longitudinal oil duct 16 is adapted to conduct the lubricant from the head of the 10 bit through the stub shaft and through a registering channel 17 in the bearing to the inner recess of the cutter.

When it is desired that this cutter be mounted upon the shaft 14, means is provided 15 for securing the cutter and bearing non-rotatably together so that the securing of the bearing upon the stub shaft may be accomplished. To do this a radial opening 18 is ordinarily formed in the cutter 20 along the largest diameter of the same, this opening being provided with threads or corrugations 19 to form a secure seat for a plug to be inserted therein. The bearing is formed with a plurality of radial recesses 20, 25 adapted to register with the openings 18 in the cutter. As shown in Fig. 2, these recesses 20 in the bearing are cut at right angles to each other and it is obvious that they may be cut at different angles, and, although 30 two recesses only are shown, it is contemplated that a larger number may be used if desired.

In mounting this cutter upon the bearing the wrench 21 is inserted into the opening 35 18 and the cutter is rotated upon the bearing until this opening registers with one of the recesses 20 in the bearing. The wrench then enters this recess and by means thereof the bearing is rotated so that it may be screwed 40 upon the stub shaft 14 and thus secured firmly in place. The wrench 21 is shown in Figs. 2 and 4. It is a straight pin having one end 22 reduced slightly in diameter 45 and rounded for use in securing a plug within the opening 18, as will be now described.

When the cutter is secured upon the stub shaft, a soft metal plug 23 is then inserted within the opening 18. This plug 23 is cylindrical on its outer surface and its inner 50 end is provided with a recess 24 somewhat V-shaped and formed to fit over the outer edge of the bearing 12, with which it is intended to contact, as shown in Fig. 1. This plug also has a rounded recess 25 in the outer end thereof to receive the smaller end 22 of the wrench. When the bearing has been secured upon the shaft 14, the cutter is rotated slightly so that the opening 18 in the cutter no longer indexes with the recess 20 in the bearing and the plug 23 is then inserted within the opening 18. The wrench 60 is fitted within the outer recess 25 in the plug and is hammered inwardly against the soft metal of the plug so as to drive it laterally, 65 and to completely fill the opening 18 and

the corrugations of the threads 19 therein so that the plug may not be removed during the operation of the cutter.

When it is desired to remove the cutter from the shaft 14, it will be necessary to 70 drive the soft metal plug inwardly into one of the recesses 20 in the bearing. To find when the opening 18 registers with the recess 20 a small nail 26, as is shown in Fig. 5, will be driven inwardly through the plug 75 against the bearing. If it strikes the hard metal of the bearing the cutter will be rotated until it is noted that the nail may be driven further into the recess. When the parts have been indexed in this manner, the 80 nail will be withdrawn and the wrench will be used as a punch to drive the soft metal plug inwardly into the recess 20. The wrench may then be inserted into the opening 18 and the cutter may be rotated upon 85 the bearing until the wrench registers with another of the recesses 20 in the bearing, after which the further rotation of the wrench and cutter will also rotate the bearing and unscrew the same from the shaft. 90

Ordinarily it is only necessary to unscrew the cutter and bearing from the drill when the teeth are dulled and it is desired to recut the teeth upon the cutter. In order that this operation of driving the plug from the 95 cutter into the bearing may be accomplished more than once or twice, it will obviously be necessary that more than two openings, or recesses 20 be provided within the bearing, but it is believed, that under ordinary 100 circumstances, two will be sufficient, it being obvious that when the cutter has been once removed and repaired it may be again secured upon the shaft and the opening through which it was last inserted may be 105 again filled with a soft metal plug, in the manner described.

The advantages of this type of means for filling the hole 18 for the wrench will be now understood. The cutter 6 is ordinarily 110 shaped and formed with the teeth thereon while the steel is still soft. The opening 18 is also cut therein while the steel is still soft. When properly machined the cutter is then submitted to heat treatment to harden 115 the metal. This treatment is apt to distort the opening 18 so that a set screw, formed to fit within this opening, will be found to be either too large or too small to accurately fit therein. By the use of a soft metal plug, 120 such as I have described, the use of a set screw may be entirely avoided and a close fit obtained at all times and at the same time the danger of losing the plug during the 125 operation of the cutter will be absolutely avoided. As will be apparent also, this plug is readily applied. It may be inserted and expanded into position by a few strokes of the hammer and when it is necessary to remove the same an ordinary nail will serve 130

to index the plug in such position relative to the recess 20 in the bearing that a few strokes of the wrench will drive the plug from its seat in the manner described.

Having thus described my invention, what I claim as new and desire to protect by Letters Patent is:

1. In a device of the character described, a frusto-conical rotatable cutter, a frusto-conical bearing formed within a central recess in said cutter, said cutter having a radial opening therein at the largest diameter of said cutter and bearing, a soft metal plug adapted to fit in said opening, said plug having a recess in the inner end to receive the edge of said bearing, and means to expand said plug within said opening.
2. In a device of the character described, a rotatable cutter having an enlarged recess therein, a bearing fitting non-removably in said recess, said bearing and cutter having radial openings adapted to register with each other, a soft metal plug adapted to fit within the opening in said cutter, means to expand said plug and means to thereafter force said plug from said cutter into the opening in said bearing.

3. In a device of the character described, a cutter shaft, a bearing having a threaded recess for attachment to said shaft, a rotatable cutter on said bearing, said bearing having a radial recess therein, and said cutter having an opening therein with corrugated sides, said opening being adapted to register with said recess, an expansible metal plug to fill said opening and means to expand said plug, and means to thereafter determine when said opening is registered with said recess.

4. In a device of the character described, a rotary cutter of hardened steel, a supporting shaft, a bearing on said shaft, fitting nonremovably in said cutter, said cutter having a radial opening therein, a recess in said bearing registered with said opening, means to close said opening comprising an expansible metal plug, means to register said plug with said recess and means to drive said plug into said recess.

In testimony whereof, I hereunto affix my signature, this the 8th day of September, A. D., 1920.

HAROLD W. FLETCHER.
